Attorneys.

UNITED STATES PATENT OFFICE.

RICHARD ROOST, OF MILWAUKEE, WISCONSIN, ASSIGNOR TO HUEBSCH MANUFACTURING COMPANY, OF MILWAUKEE, WISCONSIN, A CORPORATION OF WISCONSIN.

DISCHARGE-VALVE MECHANISM FOR USED LAUNDRY WATER.

Application filed August 20, 1919. Serial No. 318,627.

To all whom it may concern:

Be it known that I, RICHARD ROOST, a citizen of the United States, residing at Milwaukee, in the county of Milwaukee and 5 State of Wisconsin, have invented certain new and useful Improvements in Discharge-Valve Mechanism for Used Laundry Water, of which the following is a specification, reference being had to the accompanying 10 drawing, forming a part thereof.

This invention relates more particularly to valve mechanism for controlling the discharge and disposal of used laundry water.

The main objects of the invention are to 15 conserve water in the operation of laundries, especially in localities where water is scarce or is hard or impure and requires special treatment to make it suitable for washing clothes; to provide in connection with a 20 tight closing cut-off, for the discharge of a washing machine or tub, a selective valve for diverting the discharge according to its nature or condition into different conduits so that such of the wash waters, for ex- 25 ample, suds and rinsing water, as are in suitable condition, or can be practicably made so by purification or treatment, may be used over again and the rest allowed to run directly into a sewer or waste conduit; to pro- 30 vide a simple, easily assembled and installed valve unit with which the requisite pipe connections can be conveniently made for the discharge and distribution of used laundry water from washing machines, 35 laundry tubs or wash receptacles, and for the supply of fresh or clean water thereto; and generally to improve the construction and operation of apparatus for the control and disposal of the discharge from washing ma- 40 chines and tubs.

It consists in the construction, arrangement and combination of parts as herein-after particularly described and pointed out in the claims.

45 In the accompanying drawing like characters designate the same parts in the several figures.

Figure 1 is a vertical central section on the line 1—1, Fig. 2, of valve mechanism embodying the invention; Fig. 2 is a horizontal section on the line 2—2, Fig. 1; and Fig. 3 is a diagrammatic plan view on a reduced scale showing one of various ways of installing the valve mechanism with

washing machines or laundry tubs and pipe 55 lines for the conservation of used water.

Referring to Figs. 1 and 2, the valve mechanism comprises a poppet cut-off valve 1, for controlling the discharge of water from washing machines or tubs, and a 60 rotary selective plug or gate valve 2, connected with the outlet of the cut-off valve and adapted to divert or direct used laundry water discharged therefrom into different conduits, according to its nature or con- 65 dition.

The cut-off valve, which is designed primarily to directly control the discharge of used laundry water from washing machines or tubs and to tightly close the outlet from 70 each machine or tub, comprises a case 4, open at the top and provided with a removable cover 5, and closed at the bottom and provided adjacent thereto with a lateral outlet port 6. Adjacent to its lower end 75 and above the outlet port 6 the valve case is formed or provided with a beveled annular valve seat 7, and above this seat, with a lateral service port 8, with which the dis- 80 charge pipe 9 of a washing machine, laundry tub or wash receptacle is connected. The cut-off valve case is also preferably pro- 85 vided with a lateral water supply or inlet port 11, with which a pipe 12 is connected for charging the washing machine, laundry 90 tub or wash receptacle through the pipe 9 with water, according to the customary practice, without independent or extra con- 95 nections with the machine or tub for the purpose. The cut-off valve has a lift or 90 poppet valve head 14, provided with an oper- 100 ating stem 15, which extends upwardly therefrom through a stuffing box 16 in the cover 5. The valve head, which closes in the direction of the discharge flow from the port 8 to the port 6, is provided with a rub- 105 ber or elastic beveled body or face 17, fitting the seat 7 and adapted to form and maintain a tight closure therewith. A valve of this kind has been found by experience to be the only one which will satisfactorily form and maintain a tight closure for the discharge of used laundry water containing more or less soap, shreds, dirt and impurities, and it can be conveniently operated manually 105 or automatically by timing mechanism such as is used in laundries for opening the discharge outlet of a washing machine, laundry

tub or wash receptacle at predetermined times.

The selective valve 2 comprises a cylindrical case 19, closed at its lower end and formed with a lateral inlet port 20, which registers with the outlet port 6 of the cut-off valve when the parts of the apparatus are assembled as shown.

The case 19 is formed with a flanged coupling 16, which is bolted to a corresponding flanged coupling 18 on the case 4, as shown in Fig. 2, or the two valve cases may be otherwise detachably connected so that either may be replaced without discarding the other, and the construction and assemblage of parts of the device are facilitated.

The case 19, which is open at the upper end, is formed between its upper end and the inlet port 20, with lateral waste and water-saving outlet ports 22, 23 and 24. A hollow cylindrical plug gate or valve member 26, rotatably fitted in the case 19, closed at its upper end and open at its lower end in direct communication with the inlet port 20, is formed with a lateral outlet port 27, adapted to be turned into register with the outlet ports 22, 23 and 24 one at a time. The rotary plug, gate or valve member 26 is provided at its closed end with an upwardly projecting stem and handle 28.

According to one of various ways of installing the discharge valve mechanism as shown in Fig. 3, the port 8 of each cut-off valve is connected by a pipe 9 with the lower part of one of a series of washing machines, laundry tubs or wash receptacles 29. The waste outlet port 22 of each associated selective valve, is located over and in position to discharge directly into a waste conduit to 30, shown as an open gutter.

The outlet port 23 of each selective valve is connected by a branch pipe 32 with a pipe line 33 leading into a sump or reservoir 34 for saving suds or water impregnated with soap.

The outlet port 24 of each selective valve is connected by a branch pipe 36 with a pipe line 37 leading into a sump, tank or reservoir 38, for saving rinse waters.

The poppet cut-off valve 1 and the rotary selective plug or gate valve 2 being thus assembled and directly connected with each other as a unit, the piping required for the operation of washing machines, laundry tubs or wash receptacles, and the conservation of water is simplified and the installation and operation of the valves is facilitated.

In the operation of the apparatus as shown, the gate or movable member 26 of the selective valve 2 is set by the operator or attendant, while the associated cut-off valve 1 is closed, to discharge the water which has been used in the associated washing machine or tub 29, according to its na-

ture or condition, through one of the outlet ports 22, 23 or 24 of the selective valve into the gutter or waste conduit 30 or one of the pipe lines 33 or 37. If the used water is suds, or is impregnated with soap and can be made fit for further use by purification or other treatment, it is discharged through the pipe line 33 into the sump or reservoir 34 in which impurities are allowed to settle and the soap is recovered and from which it is drawn for further use in a washing machine or tub.

If the used water, such as rinse water, does not contain soap and is suitable with or without treatment, for further use, it is discharged through the pipe line 37 into the tank or reservoir 38, in which impurities, if any, are allowed to settle, and from which it is drawn as needed.

If the used water discharged from a machine or tub is unfit for further use, and it is impracticable to make it fit for further use, it is discharged directly from the selective valve into the waste conduit 30.

The selective valve may be provided with one or more outlet ports and pipe connections for saving used water, according to the conditions and requirements of the laundry in which it is installed.

Various changes in details of construction and arrangement of parts of the valve mechanism or apparatus may be made without departure from the principle and scope of the invention as defined in the following claims.

I claim:

1. The combination of a cut-off valve for controlling the discharge of used laundry water comprising a case provided with a seat, a service port on the same side of the seat and an outlet port and coupling member on the opposite side of the seat, and a poppet valve head adapted to close in the direction of discharge flow tightly against the seat; and a selective valve comprising a cylindrical case provided with outlet ports and with an inlet port and coupling member registering with the outlet port and coupling member of the cut-off valve, and a hollow cylindrical gate rotatably fitted in the selective valve case in open communication at one end through its inlet port with the outlet port of the cut-off valve and provided with a port registrable with the outlet ports of the selective valve one at a time.

2. The combination of a cut-off valve for controlling the discharge of used laundry water comprising a case provided with a valve seat, service and water-supply ports on the same side of the seat and an outlet port and coupling member on the opposite side, and a poppet valve head adapted to close in the direction of discharge flow tightly against the seat; and a selective valve comprising a cylindrical case provided with

outlet ports and with an inlet port and coupling member registering with the outlet port and coupling member of the cut-off valve, and a hollow cylindrical gate rotatably fitted in the selective valve case in open communication at one end through its inlet port with the outlet port of the cut-off valve and

provided with a port registrable with the outlet ports of the selective valve one at a time. 10

In witness whereof I hereto affix my signature.

RICHARD ROOST.
